(57) **CLAIM**

The ornamental design for a fishing rod holder and belt, as shown and described.

DESCRIPTION

FIG. 1 is a perspective view of the design showing a fishing rod holder and belt;

FIG. 2 is a front elevational view of the design shown in FIG. 1;

FIG. 3 is a top plan view of the design shown in FIG. 2;

FIG. 4 is a rear elevational view of the design shown in FIG. 2;

FIG. 5 is a bottom plan view of the design shown in FIG. 4;

FIG. 6 is a right side elevational view of the design shown in FIG. 2; and,

FIG. 7 is a left side elevational view of the design shown in FIG. 2.

Shading is not part of the design but only to illustrate curvatures and surface design.

The features shown in broken lines depict environmental subject matter only and form no part of the claimed design.
